United States Patent [19]

Ching et al.

[11] Patent Number: Des. 289,034

[45] Date of Patent: ** Mar. 31, 1987

[54] FRONT FACE OF A CONTROL PANEL FOR NUCLEAR REACTOR POWER MONITOR SYSTEM

[75] Inventors: **Walter S. Ching**, Sunnyvale; **Edward M. Chu**, Los Altos; **Alan B. Jones**, Los Gatos; **Randall J. Collins**, San Jose; **Barry H. Simon**, Santa Clara; **Lyle H. McCarty**, Saratoga, all of Calif.

[73] Assignee: **General Electric Company**, San Jose, Calif.

[**] Term: **14 Years**

[21] Appl. No.: **671,980**

[22] Filed: **Nov. 16, 1984**

[52] U.S. Cl. **D13/35**

[58] Field of Search ..... **D13/12, 32, 35, 40-41, D13/99; 361/331-332, 334, 380, 390; 174/50, 52 R, 65 R; D14/114; 376/216-217; D10/46-47, 49, 78, 96, 101**

[57] CLAIM

The ornamental design for a front face of a control panel for nuclear reactor power monitor system, as shown and described.

DESCRIPTION

The FIGURE is a front elevational view of a front face of a control panel for nuclear reactor power monitor system showing our new design.

The white areas represent openings and the black surface represents a dark color.
